ROTARY SPRAYER

Harry C. Lassen, San Jose, Calif., assignor to
Food Machinery Corporation, San Jose, Calif.,
a corporation of Delaware

Application July 13, 1933, Serial No. 680,167

8 Claims. (Cl. 299—69)

The present invention relates to certain new and useful improvements in the construction of rotary sprayers such as are operable by the flow of liquid therethrough.

- 5 The liability of rotary sprayers to stick or bind, particularly after periods of idleness, and thereby interfere with or prevent automatic starting when the liquid is next supplied to them, is well known, and under some circumstances a very 10 considerable force may be required to overcome starting resistance as, for example, where the sprayer is required to operate under high liquid pressures or to spray certain kinds of liquid mixtures or solutions.
- 15 As illustrative of one instance in which rotary sprayers may be required to operate under such conditions, reference may be had to United States Letters Patent No. 1,912,209, issued May 30, 1933, to myself and Henry Dahl jointly, wherein is 20 described the use of rotary sprayers adapted to discharge spray liquids into greenhouses in the form of a finely divided fog-like mist to control temperature or apply liquid insecticidal or fungicidal agents to the plants. The breaking up or 25 atomization of the liquid to a sufficient fineness for the purpose requires that it be delivered to the spray nozzles under comparatively high pressures, which may range as high as 400 or even 600 pounds per square inch, and it will be appreciated that such high pressures cause great frictional resistance in the bearing members of the sprayer which, in addition to the inertia of the parts, must be overcome in order to start rotation. Moreover, the initial starting impulse 30 required is frequently greatly increased when spray liquids such as insecticides or fungicides are used which may contain more or less sediment, or may leave a crystalline or gummy residuum when evaporated, so that during periods of idleness, 35 after being used with such a liquid, the liquid may evaporate from the interior of the sprayer leaving a deposit of sediment, crystals, or gummy residue around the bearings, which causes them to stick or bind and thereby interfere with automatic starting when use is next attempted.

In order to insure reliable automatic starting, it will be obvious that the sprayer must be so constructed that the torque exerted by the flow of liquid through it will be sufficient to overcome the 50 severest resistance to starting which may be encountered. Because of the fact, however, that the torque required to maintain rotation of the sprayer at the proper speed after it is once set in motion is considerably less than the torque required to start the sprayer from rest, the con-

tinued application of the initial starting torque causes the sprayer to race at an excessive speed once it is set in motion, with the result that the effective range or radius of discharge is undesirably reduced. It will be understood that the distance to which the spray is discharged decreases as the speed of rotation of the sprayer is increased, and consequently, for most efficient operation, it is desirable to limit the speed of rotation. For example, sprayers such as are adapted to atomize the liquid into a sufficiently finely divided fog-like mist for the greenhouse work referred to should preferably not be rotated more than 8 or 12 R. P. M. for most effective operation.

On the other hand, if the sprayer be so constructed that the rotative force exerted by the liquid passing through it is only just sufficient to maintain the sprayer in operation at the proper speed, such force frequently will not be sufficient to start the sprayer from rest. Moreover, the liquid pressure in the supply mains is frequently subject to variations, which cause a corresponding variation in the rotative energy supplied by the liquid passing through the sprayer, which may cause the sprayer to stop or run too slow unless the sprayer is constructed to insure a torque in excess of ordinary running requirements.

It is the general object of the present invention to provide a rotary sprayer operable by the flow of liquid therethrough which can be depended upon for automatic starting and which, in operation, will rotate at a selected and uniform speed.

More specifically, it is an object to provide a rotary sprayer constructed to receive sufficient torque by the energy of the liquid passing therethrough to insure automatic starting, and having a suitable speed governor associated therewith which will come into play as the sprayer accelerates to limit the maximum speed of rotation of the sprayer.

It is also an object to provide a rotary sprayer with a speed governing device comprising an air foil or vane mounted for rotation about the rotative axis of the sprayer and normally held edge-wise to its direction of travel, but swingable broadside to its path of travel under the influence of centrifugal force to provide sufficient air resistance to limit the rotative speed of the sprayer.

A further object of the invention is to provide a rotary sprayer with a discharge nozzle or nozzles which may be angularly adjusted to vary the direction of discharge therefrom and the resulting reactive torque produced by said discharge, together with a suitable speed governing mecha-

nism which may be adjusted to vary its limiting effect upon the rotation of the sprayer.

Another object is to provide a rotary sprayer with a supplementary discharge nozzle mounted 5 for universal movement whereby its discharge may be directed in any direction desired.

Additional objects and advantages will become apparent as the description proceeds in connection with the accompanying drawing, in which:

10 Figure 1 is a side elevation of a rotary sprayer constructed in accordance with the present invention.

Figure 2 is a plan view of the sprayer shown in Figure 1.

15 Figure 3 is a sectional view taken along the line 3-3 of Figure 2, illustrating the air foil to somewhat larger scale.

In the illustrated embodiment, the sprayer includes a hollow distributor head 1 carrying the 20 outwardly projecting pipes 2 which form liquid distributing arms through which the liquid passes from the interior of the distributor head to the spray nozzles 3 mounted on the outer ends of the arms and to the intermediate spray nozzle 4. The 25 sprayer may be supplied with liquid from a supply pipe 5 communicating with the interior of the distributor head and upon which said distributor head is rotatably journaled. A retaining ring 6 screwed to the lower end of the distributor head 30 serves to hold a suitable packing in place within the head, in a manner well known in the art, to prevent leakage.

35 The spray nozzles 3 are adjustably mounted on the outer ends of the arms 2 by pairs of elbow pipes 7 and 8 secured together by screw and thread engagement so that the nozzles 3 may be turned to any desired angle with respect to the arms 2. As the reactionary force supplied by the liquid discharged from the nozzles 3 supplies the motive 40 power for rotating the sprayer, it will be seen that by adjusting the angularity of the nozzles with respect to the arms 2 the torque applied to the sprayer may be correspondingly varied according to the force required to insure automatic and immediate starting.

45 As hereinbefore explained, when the nozzles are set to produce a sufficient reactionary force to insure that it will overcome any sticking or binding which may occur between the head 1 and the 50 supporting pipe 5 upon which it is journaled, as well as the inertia of the sprayer itself, and result in immediate and certain automatic starting of the sprayer when liquid is supplied to it, the resulting speed of rotation of the sprayer, once it 55 is started in operation, may be so rapid as to unduly limit the range or radius to which the liquid is discharged.

60 In order to limit the rotation of the sprayer to the desired speed, and insure uniformity of rotational speed irrespective of liquid pressure variations, a speed governing device is provided which may include an air foil or vane 9 mounted upon one of the arms 2 for rotation therewith about the 65 rotational axis of the sprayer. In the device shown, the foil 9 is made up of a rectangular piece of sheet metal, although, as will be understood, other materials or shapes might be used if desired.

70 The foil 9 is mounted for swinging movement about a vertically disposed rod 10, and this may be conveniently accomplished by curling one edge of the foil into the form of a sleeve 11 to form a bearing rotatably journaled on the rod 10. The outer end of the air foil may be weighted as by means of a weight 12 secured to one of its faces 75 so as to cause it to swing outwardly toward a posi-

tion broadside to its path of travel, under the influence of centrifugal force.

The rod 10 is secured to and projects upwardly 80 from the upper section of a split clamp 13 firmly secured in place on the arm 2 by bolts 14 passing through the ears 15 of the clamping sections and provided with nuts 16. One of the bolts 14 is extended as shown to form a stop 17 against which the foil 9 normally rests.

85 A bracket 18 has one end bent around the arm 2 and is clamped to the arm by a bolt and nut 19 and is provided with a plurality of holes 20 into one of which is hooked one end of a coil spring 21, the other end of the spring being hooked through 90 one of a series of holes 22 along the lower edge of the air foil 9, so that the spring normally holds the foil against the stop 17 in edgewise position to its direction of travel where it offers the least air resistance. As may be seen, the tension of the spring 21 may be adjusted as desired by hooking its ends through any of the holes 20 and 22, or by shifting the bracket 18 to a different position on the arm 2, which may be done after loosening the clamping bolt and nut 19.

95 In some instances it may be desirable to provide the sprayer with one or more auxiliary nozzles which can be arranged to discharge to a different point than the main nozzles. For example, in greenhouses certain kinds of plants may grow to a height considerably above the elevation of the sprayer, in which event the upper portions of the plants may not be effectively subjected to the discharge from the main nozzles unless these nozzles are turned in an upward direction, which is undesirable because of the resulting reduction in 100 the reactive torque produced by the sprays. Sometimes, also, it may be desirable to direct a portion of the spray downward for more effective application to lower parts of the plants, or to small plants beneath the sprayer.

105 Again, where rotary sprayers are utilized in greenhouses for controlling temperature according to the method described in the patent above referred to, in which the sprayers are operated to fill the greenhouse with a finely divided fog-like mist of cooling liquid, it may be desirable to project a part of the spray in an upward direction to insure rapid and effective filling of the greenhouse with the mist.

110 For such purposes, the sprayer may be provided with an auxiliary nozzle 4 which is mounted intermediate the length of one of the arms 2 by means of a pair of elbow pipes 23 in screw threaded engagement with each other, the inner elbow being screwed onto a nipple 24 projecting 115 from the arm 2. This construction provides a universal mounting for the auxiliary nozzle 4, whereby it can be adjusted to discharge in any direction desired, thus augmenting the discharge from the main nozzles to cover a greater area, or 120 to supply additional torque to the sprayer. It will be understood that although only one auxiliary nozzle is illustrated, others may be provided as desired, either on the same arm or on the other one.

125 The operation of the sprayer will now be apparent. The liquid to be sprayed is supplied to the interior of the chambered distributor head from the pipe 5 and passes through the arms 2 to the nozzles 3 and 4, from whence it issues in the 130 form of a spray of any desired fineness, according to the pressure of the liquid and the size of the nozzle openings. The nozzles 3 may be set at whatever angle required to supply sufficient torque to insure prompt and automatic starting, 135

and the auxiliary nozzle 4 may be adjusted to any desired position to increase the area of coverage or to increase the torque applied to the sprayer. At the lower speeds, the air foil 9 is held by the spring 21 against the stop 17 in edgewise relation to its path of travel, where it offers little or no air resistance, but as the sprayer accelerates the air foil is caused to swing outwardly under the influence of centrifugal force toward a position broadside to its path of travel, thereby increasing its air resistance and retarding the rotation of the sprayer so as to limit its rotation to a proper and uniform speed. By suitably adjusting either or both the spring 21 and the angularity of the nozzles 3 a very delicate control over the maximum speed of rotation may be had, as will be apparent.

Having now described my invention, it will be understood that various changes and modifications may be resorted to without departing from the spirit of, or sacrificing any of the advantages of the invention, and I deem myself entitled to all such variations and modifications as fall within the scope of the claims appended hereto.

25 What I claim as new and desire to protect by Letters Patent is:

1. In a rotary sprayer operable by the flow of liquid therethrough, a spraying assembly including a rotatably mounted chambered distributor head, a liquid distributing arm projecting outwardly from said head, and a liquid discharge nozzle carried by said arm, an air foil associated with said assembly for rotation therewith around its rotative axis and mounted for swinging movement broadside to its path of travel under the influence of centrifugal force to retard the rotative speed of said assembly, and yieldable means for urging said air foil into a normal position edgewise to its direction of travel.

2. In a rotary sprayer operable by the flow of liquid therethrough and having a rotatably mounted chambered distributor head, and liquid distributing and discharge means projecting outwardly from said head, a swingably mounted air foil associated with said sprayer for rotation therewith around its rotative axis, and yieldable means for normally holding said air foil in a position to offer a minimum of air resistance, but permitting said air foil to swing outwardly under the influence of centrifugal force toward a position of maximum air resistance.

3. In a rotary sprayer operable by the flow of liquid therethrough, a liquid supply pipe, a chambered distributor head rotatably journaled thereon, a liquid distributing arm projecting outwardly from said head, a liquid discharge nozzle on said arm, an air foil mounted on said arm for swinging movement broadside to its path of travel under the influence of centrifugal force to retard the rotative speed of said sprayer, and yieldable means interconnecting said air foil and arm for urging said air foil into a normal position edgewise to its direction of travel.

4. In a rotary sprayer, a liquid supply pipe, a chambered distributor head rotatably journaled thereon, a liquid distributing arm projecting outwardly from said head, a liquid discharge nozzle carried by said arm from which issuing liquid produces a reactive torque sufficient to rotate said

head at an excessive speed, a plane surfaced air vane mounted on said arm for swinging movement broadside to its path of travel under the influence of centrifugal force to retard the rotative speed of said sprayer, and yieldable means interconnecting said vane and arm for urging said vane into a normal position edgewise to its direction of travel.

5. In a rotary sprayer operable by the flow of liquid therethrough, a spraying assembly including a rotatably mounted chambered distributor head, a liquid distributing arm projecting outwardly from said head, and a liquid discharge nozzle carried by said arm, a plane surfaced air vane associated with said assembly for rotation therewith around its rotative axis, said air vane being swingable about a vertical axis and having a weighted outer end to assist in swinging the vane broadside to its path of travel under the influence of centrifugal force to retard the rotative speed of said assembly, and yieldable means for urging said air vane into a normal position edgewise to its direction of travel.

6. In a rotary sprayer operable by the flow of liquid therethrough, a spraying assembly including a rotatably mounted chambered distributor head, a liquid distributing arm projecting outwardly from said head, and a liquid discharge nozzle carried by said arm, a plane surfaced air foil mounted on said arm for rotation therewith and for swinging movement about a vertical axis, said air foil having a weighted outer end to assist in swinging the foil broadside to its path of travel under the influence of centrifugal force to retard the rotative speed of said assembly, and yieldable means for urging said air foil into a normal position edgewise to its direction of travel.

7. In a rotary sprayer, a spraying assembly including a rotatably mounted chambered distributor head, a liquid distributing arm projecting outwardly from said head, and a liquid discharge nozzle adjustably mounted on said arm to permit variation of its direction of discharge and the resulting reactive torque produced by said discharge, an air foil associated with said assembly for rotation therewith around its rotative axis, and mounted for swinging movement broadside to its path of travel under the influence of centrifugal force to retard the rotative speed of said assembly, yieldable means for urging said air foil into a normal position edgewise to its direction of travel, and means for varying the yieldability of said yieldable means.

8. In a rotary sprayer, a liquid supply pipe, a chambered distributor head rotatably journaled thereon, a liquid distributing arm projecting outwardly from said head, a liquid discharge nozzle adjustably mounted on said arm to permit variation of its direction of discharge and the resulting reactive torque produced by said discharge, a plane surfaced air vane mounted on said arm for swinging movement broadside to its path of travel under the influence of centrifugal force to retard the rotative speed of said sprayer, yieldable means for urging said air vane into a normal position edgewise to its direction of travel, and means for varying the yieldability of said yieldable means.

HARRY C. LASSEN.
